UNITED STATES PATENT OFFICE.

WILLIAM DOWNS, OF TORONTO, CANADA.

RUBBER HORSESHOE.

No. 800,634.

Specification of Letters Patent.

Patented Oct. 3, 1905.

Application filed September 26, 1904. Serial No. 225,882.

To all whom it may concern:

Be it known that I, WILLIAM DOWNS, a subject of the King of Great Britain, residing at Toronto, in the county of York, in the Province of Ontario, Canada, have invented a new and useful Improvement in Rubber Horseshoes, of which the following is a specification.

The objects of my invention are to construct a rubber horseshoe that may be readily put on or removed in the event of wet or slippery roads.

In the construction of the shoe it is so formed and provided with fastening means that it may be arranged to fit or fasten to any size or shape of foot.

In fastening the shoe to the foot detachable means are provided whereby nails or clamping means are eliminated, thereby avoiding impairment to the rubber that is used in the construction.

The construction and means of fastening the shoe to the foot are so arranged that stubbing or striking the shoe against obstacles will not remove it from its place.

I attain these objects by my invention, as illustrated in the accompanying drawings, in which—

Figure 1 is a perspective view of a horse's hoof, showing the rubber shoe in position. Fig. 2 is a plan view of the bottom of the rubber shoe. Fig. 3 is a perspective view of the rubber shoe removed. Fig. 4 is a longitudinal section view on lines 2 2, Fig. 3. Fig. 5 is a perspective view of the metal plate removed, and Fig. 6 is a side elevation of the metal plate.

Like letters refer to like parts throughout the specification and drawings.

The shoe consists, practically, of a rubber pad *a*, molded to conform to the shape of the bottom of the hoof and may be of any desired thickness. In the upper and front edge of the pad is a cut-away section *b*, adapted to receive the toe-calk of the metal shoe *c*, and each of the back calks *d* is adapted to fit into cut-away sections *e* at the back upper edge of the pad. Laterally extending through the sides of the pad near the back end are studs *f*, and projecting upward and forward from the front of the pad is a lug *g*, the lug *g* being adapted to fit under the edge of the metal shoe *c* between the hoof. In the bottom of the pad *a* is a cushion-groove *h*, which also acts to lighten the pad. The balance of the bottom, with the exception of a small section at the front or toe part, is diagonally grooved or channeled to

prevent slipping and also to provide a finished surface.

In the construction of the rubber shoe I provide a metal plate *i*, around which the rubber is molded. The plate *i* consists of a thin sheet of metal formed to the exact shape of the bottom of the hoof. The lug *g* is formed by being stamped out and bent at right angles and then parallel with the plane of the plate *i*. Stamped out and bent downward from the obverse side of the plate *i* from the lug *g* are a series of small lugs *j*. The lug is formed deep enough to extend through the thickness of the rubber on the upper face of the plate; but the lugs *j* are arranged so that they do not project through the rubber on the under side of the plate. The circumference of the plate *i* will be of a slightly smaller scale than the rubber pad *a*, so that none of the plate *i* will extend through the edge of the pad. Riveted to the plate *i* is a strengthening-bar *k*, which extends across and beyond the edges of the plate and forms the studs *f*, extending through the sides of the pad. 80

The shoe or pad is molded with the plate *i* in the interior or slightly nearer the upper part, the rubber forming through the openings *l*, formed by stamping out the lugs *j* and lugs *g*, and by this form it will be understood that the rubber will not slide on the plate, and it will also be prevented from moving by the lugs *j* and *g*, extending into the pad.

The shoe or pad *a* may be molded so as to extend considerably beyond the edge of the plate *i* that it may be cut down to conform to the different sizes and shapes of hoofs.

In fitting and fastening the rubber shoe to the foot of the horse the pad will be cut down to the exact size and shape of the bottom of the hoof, the cut-away sections *b* and *e* being trimmed out to fit exactly with the front and back calks, respectively. Then for fastening the pad to the foot the lug *g* is forced between the hoof and the shoe *c*, and a rubber band *m*, provided at each end with a triangular-shaped metal loop *n*, the loops *n* being adapted to fasten over the studs *f*, is brought over the hoof, as shown in Fig. 1. The band *m*, engaging with the studs *f* and extending over the hoof, as shown, allows for any play or necessary movement that might occur when the animal's foot strikes the ground; but the tautness of the rubber band will prevent it, with the aid of the calks and the lug *g*, from becoming misplaced. 110

It will be seen that by constructing a rubber

shoe as described it is adaptable to be fitted to any style or shape of a metal shoe and may be readily attached or removed without interfering with the metal shoe, as no nails are 5 used in fastening the rubber shoe to the animal's foot.

Damage is entirely eliminated to the rubber shoe, with the exception of wear and tear caused by usage.

10 What I claim as new, and desire to secure by Letters Patent, is—

15 1. In a rubber horseshoe, a rubber pad molded to conform to the shape of the bottom of the horse's hoof, said rubber molded around a metal plate, said plate shaped substantially the same shape as the bottom of the hoof, a series of lugs stamped out of said metal plate, and adapted to extend down into said rubber pad, a lug stamped out of said metal plate and 20 adapted to extend upward through said rubber pad—thence forward parallel to the plane of the said metal plate, a strengthening-bar riveted and adapted to extend across and beyond the edges of said plate, substantially as 25 described.

2. In a rubber horseshoe, a metal plate shaped to conform to the shape of the bottom of the hoof, a series of lugs stamped and bent downward at right angles with said plate, a 30 fastening-lug formed in said plate by stamping and bending at right angles—thence parallel with the said plate, a strengthening-bar riveted across said plate, said bar adapted to extend beyond each side of said plate, said 35 projecting ends adapted to form the fastening-studs, said plate adapted to be molded within a rubber pad, substantially as described.

3. In a rubber horseshoe, a rubber pad molded to conform to the shape of the bottom 40 of a horse's hoof, said pad being molded over a metal plate substantially the same shape as the said pad, a fastening-lug formed in said plate adapted to extend upward through said pad, fastening-studs riveted to said plates and 45 adapted to extend through the sides of said rubber pad, means for detachably fastening said pad to the horse's hoof, substantially as described.

4. In a rubber horseshoe, a rubber pad 50 molded to conform to the shape of the bottom of a horse's hoof, a cushion-groove formed in the bottom of said pad, fastening-studs projecting from the side edges of said pad, a fastening-lug projecting upward and forward from the top plane of said pad, cut-aways in 55 the front and back of said pad, said cut-aways adapted to engage with the front and back calks of the metal shoe, the said lug adapted to engage between the horse's hoof and the said metal shoe, an elastic band adapted to fasten 60 said pad to the horse's hoof, said band having metal loops adapted to fasten over the studs projecting from the side edges of said pad, substantially as described.

5. In a rubber horseshoe, a rubber pad 65 molded to conform to the shape of the bottom of a horse's hoof, a fastening-lug projecting from the top of said pad, fastening-studs projecting from the side edges of said pad, said lugs adapted to engage between the horse's 70 hoof and metal shoe, an elastic band arranged to detachably fasten said pad to the horse's hoof, said band having at each end a metal loop adapted to engage with the said projecting studs, and said band adapted to stretch 75 over the said horse's hoof, substantially as described.

6. In a rubber horseshoe, a rubber pad conforming to the shape of the bottom of the hoof, cut-aways in the front and back edges 80 of said pad, said cut-aways adapted to engage with the calks of the metal horseshoe, a lug projecting upward from the top of said pad, studs projecting from the side edges of the said pad, an elastic band having metal loops 85 at each end adapted to engage with said studs, said band adapted to extend over the hoof and hold pad in position on said hoof by the combination of the said lug, substantially as 90 described.

Signed at Toronto this 22d day of September, 1904.

WILLIAM DOWNS.
